UNITED STATES PATENT OFFICE.

HENRY A. BROWN, OF HUNTINGTON, WEST VIRGINIA, ASSIGNOR OF ONE-THIRD TO GUY E. SHINKLE AND ONE-THIRD TO FRANK M. WHITE, BOTH OF HUNTINGTON, WEST VIRGINIA.

RE AND DE RAILING DEVICE.

Application filed December 13, 1922. Serial No. 606,707.

To all whom it may concern:

Be it known that I, HENRY A. BROWN, a citizen of the United States, residing at Huntington, in the county of Cabell and State of West Virginia, have invented a new and useful Re and De Railing Device, of which the following is a specification.

This invention relates to car deraillers and replacers which are commonly termed "jumpers".

The object of the invention is to provide a device of this character constructed for removing and replacing a car from the end of a track.

Another object is to provide a device of this character equipped with means to detachably engage a track rail and hold the jumper against sidewise movement, making a firm connection with the track rail.

Another object is to so construct a device of this character that a car may be easily replaced with a minimum amount of exertion.

Another object is to construct a device of this character to adapt it for use in loading cars in mines whereby the car may be loaded from either side or end or both.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents a plan view of a jumper constructed in accordance with this invention.

Fig. 2 is a side elevation thereof.

Fig. 3 is an end elevation taken from the left hand end of Fig. 1, and

Fig. 4 is a similar view taken from the right hand end.

In the embodiment illustrated, the car derailler and replacer or jumper 1 constituting this invention comprises two rail sections 2 and 3 arranged parallel for a portion of their length, 2 constituting what may be termed the main rail and 3 the guard rail. The guard rail 3 has its inner end deflected as shown at 4 to facilitate the passage of a

car wheel from the main track rail, not shown, onto the jumper.

A plate 5 connects the inner ends of the rails 2 and 3, being inserted under the bases thereof, and preferably riveted thereto as shown clearly in Fig. 1, and which secures the rails in operative relation. This base or connecting plate 5 is provided in its side edges near its outer end with downstruck spurs 6 designed to be driven into the wooden tie to assist in holding the jumper in operative position in regard to the track rail. The notches 7 formed by striking out these spurs 6 may also be used for the insertion of spikes, not shown, to assist in holding the device rigidly in position.

The outer ends 8 and 9 of the main and guard rails diverge as is shown clearly in Fig. 1, and are connected by a triangular plate 10 riveted to the flanges thereof, and which is made concave as shown in Fig. 3 to facilitate the passage of the car wheel onto the jumper when a car is to be replaced.

Secured to the inner end of the main rail 2 are two flat steel strips 11 and 12 which are superposed on the flanges of said rail and riveted thereto, projecting at one end beyond the inner end of the rail and having their terminals rounded as shown at 13. This arrangement of the strips 11 and 12 on opposite sides of the web of the rail 2 positions them apart a sufficient distance to adapt the projecting ends to straddle the web of the track rail to which the jumper is designed to be applied, and which prevent its moving laterally relatively to the track rail.

The inner ends of the main and guard rails 2 and 3 are bent downwardly as shown clearly in Fig. 2 and these bent ends are designed, when the device is applied to extend longitudinally outward from the track rails, the jumper inclining downwardly and outwardly so that the car passing thereover will be guided gradually downward to the surface onto which it is to be moved. The car is about six to eight inches higher when on the main track than when it is lowered by the jumpers. This is of very great advantage in low coal.

These jumpers 1 are made in rights and lefts and are adapted to be jointed to the ends of the rails of the track, the guard rail

3 of each jumper being disposed on the inside of the track.

These jumpers eliminate certain objections which characterize the present methods of loading cars in mines, obviating the necessity of laying the main track close to the coal which is going to be shot down, and thus rendering it unnecessary to shovel out the coal so the car can be used. Tracks are generally laid in coal mining work, within three feet of the coal, which renders it necessary to tear up the track when a machine cutter is to be used, since the track interferes with the operation. After the coal has been cut by the cutting machine, the track must be relaid to enable the car to be placed in proximity to the coal which causes much delay in addition to the extra work required.

20 The use of this jumper eliminates these objectionable features since instead of laying the track up to within three feet of the face of the coal, it may be laid within nine feet from the face of the coal and these jumpers which are three feet long are laid at the end of the track. This makes the distance between the end of the jumper and the face of the coal about six feet, thus allowing ample room for the coal to fall on a smooth floor when shot down.

Then as the coal car is loaded, it is run off the jumper onto the hard floor close to the coal so that the cars may be loaded from the side as well as from the end, thus greatly facilitating loading of the cars.

It will thus be seen that the use of these jumpers in coal mining greatly reduces the labor and increases the output as well as eliminating many wrecks.

40 I claim:—

1. A device of the class described comprising a main rail and a guard rail rigidly se-

cured together and arranged in parallel relation, means for connecting one end of the main rail to a track rail, and means at the other end to facilitate the passage of the car onto the device.

2. A device of the class described comprising a pair of rail sections arranged in parallel relation, one of said rails being deflected outward at one end and the other provided with means for detachably connecting it to a main track rail, plates connecting said rail sections rigidly together, the outer ends of said rail sections diverging.

3. A device of the class described comprising a pair of rail sections arranged in parallel relation, one of said rails being deflected outward at one end and the other provided with means for detachably connecting it to a main track rail, plates connecting said rail sections rigidly together, the outer ends of said rail sections diverging, a triangular plate connecting said diverging ends and made concave at its outer end to facilitate the passage up thereon of a car wheel.

4. A device of the class described comprising a pair of rail sections arranged in parallel relation, plates connecting the ends of said sections, a pair of steel strips secured to the flanges of one of said sections at one end thereof and projecting beyond said end to provide means for detachable engagement with a track rail, and means to facilitate the passage onto said rail sections of the wheel of a car to be replaced.

In testimony that I claim the foregoing as my own, I have hereto affixed my signature in the presence of two witnesses.

HENRY A. BROWN.
